Inventor

Herman H. A. Lehmann

UNITED STATES PATENT OFFICE.

HERMAN H. A. LEHMANN, OF NEW ORLEANS, LOUISIANA.

COOLING REFRIGERATOR.

Application filed February 17, 1925. Serial No. 619,652.

To all whom it may concern:

Be it known that I, HERMAN H. A. LEHMANN, a citizen of the United States, residing at New Orleans, in the parish of Orleans and State of Louisiana, have invented certain new and useful Improvements in a Cooling Refrigerator, of which the following is a specification.

This invention relates to cooling refrigerators, and has for its prime object to provide means for keeping kegged beer or other beverages cooled while dispensing same.

A further object of the invention is to provide means for not only dispensing kegged beer, but also for cooling bottled beverages and also storage space for reserve stock of kegged goods.

A still further object of the invention is to provide a cooler, which is adapted to contain a number of kegged goods, and whereby the kegs may be easily and quickly entirely withdrawn from the cooler so that same can be removed from the supporting platforms and new kegs replaced thereon.

Another object of the invention is to provide a cooler of the above indicated character, which is simple in construction, durable, efficient for the purpose intended and one that can be manufactured and placed on sale at a relatively low cost.

These and like objects of the invention will be better understood as the description follows and as is specifically pointed out in the appended claims.

Referring to the accompanying drawings which form a part of this specification and which clearly illustrate the construction and operation of my invention,

Figure 1 is a perspective view of a cooler constructed in accordance with my invention.

Figure 2 is a vertical section through same.

Figure 3 is a section of my improved cooler with the front wall removed, and

Figure 4 is a side elevation of one of the keg supports.

Referring to the accompanying drawings in detail, like characters will be used to designate like parts in the different views.

In the drawings, the numeral 1 indicates as a whole a cooler constructed in accordance with my invention. It is to be understood that while I have only shown my cooler constructed with a pair of upper and lower compartments having doors 2 opening

therein, that I reserve the right to use as many compartments as I desire. Each of the doors 2 has secured thereto on the inner side a sliding rack 3 which is provided with cross braces 4 and a keg of beer or other beverage as indicated by the numeral 5 is adapted to be supported on the cross braces 4 of each of the sliding racks 3, as is clearly indicated in Figures 2, 3, and 4. The kegs positioned in the upper compartments are adapted to be supported in such a position that the front ends of same can be readily tapped for dispensing liquid therefrom. A tap 6 is connected to one end of the barrels 5 in the upper compartments by passing taps through openings formed in the doors 2, and a flexible hose 7 is connected to the opposite end of each of the barrels, and the opposite end of the hose 7 is connected to a pipe 8 which runs to any suitable source of compressed air reservoir, so that by opening the valve 9 in the pipe 8, compressed air is permitted to enter the kegs in the upper compartments and dispense the beverage through the tap 6.

The rear wall 10 of the cooler is provided adjacent its upper edge with trap doors 11, which are two in number, one positioned behind each of the kegs 5 in the upper compartments. The trap doors 11 permit means for extending the hand into said cooler for coupling the hose 7 to the pipe 8 and to operate the valve 9 for allowing compressed air to enter the kegs.

Supported in any suitable way on top of the cooler at a point above the upper chamber, is a perforated partition 12, whereby bottled goods and ice may be placed therein through doors 13. Thus it will be seen that the drippings from the ice will pass over the kegs in both the upper and lower compartments, thus not only keeping the kegs from which the beverage is being dispensed cool, but also the kegs stored in the lower compartments.

Extending horizontally across the cooler at the bottom and in the middle of same are a series of rollers 14, on which the racks 3 are supported, so that the racks and kegs supported thereon can be withdrawn from the cooler by pulling outwardly on one of the doors 2. By supporting the racks and kegs in such a manner the kegs can be first arranged on the racks and placed in the lower compartment in order that the beverage therein may be cooled while beverage is

being dispensed from the kegs in the upper compartment, and when the kegs in the upper compartment become empty, the rack supporting the same may be entirely removed from the cooler and a keg from the lower compartment substituted therefor without either of said kegs being removed from the rack upon which it was originally placed. The object in moving the kegs to the upper compartment is to position the same so that the beverage may be conveniently dispensed therefrom. It will be noted that the doors 2 of the cooler are carried by the racks in order to eliminate the necessity of removing the taps 6 when opening or closing the doors.

From the foregoing description of my invention taken in connection with the accompanying drawings, it can be readily seen that I have provided an improved cooling chamber for the dispensing of beverages from kegs, which is absolutely sanitary, as the liquid passes directly from the keg to the tap or faucet, thus eliminating all coils or other intervening cooling devices which accumulate deposits or sediments which are dangerous to health, or destroy the original flavor of the beverage. This is especially true in the case of beer, it being a recognized fact to brewers and others versed in the manufacture of beer and other beverages. It will also be observed that my improved cooler serves three distinct purposes, namely: the storage of kegged goods, supporting kegged goods on tap for dispensing, and also a cooling chest for bottled goods.

It is to be understood that the form of my invention herewith shown and described is to be taken as a preferred example of the same, and that various changes as to the shape, size, and arrangement of parts may

be resorted to, without departing from the spirit of the invention or the scope of the subjoined claims.

What I claim as new and desire to secure by Letters Patent is:

1. A cooler comprising a compartment having a pair of door openings arranged therein, a pair of keg supporting racks adapted to be received in said compartment by passing the same through said openings, doors carried by said racks for closing said openings when said racks are received in the compartment, rollers arranged in the compartment for receiving and supporting said racks and kegs, said racks being identical in construction and arranged in the compartment so that one of said racks with the keg thereon may be substituted in the place of the other rack and keg.

2. In a cooler comprising a compartment having a pair of door openings therein, a pair of keg supporting racks adapted to be received in said compartment by passing the same through said openings, doors carried by said racks for closing said openings when said racks are received in said compartment, rollers arranged in the compartment for receiving and supporting said racks and kegs, each of said doors having an opening therein to permit a tap to extend therethrough for tapping said kegs, said racks being identical in construction and arranged in the compartment so that one rack with the keg thereon may be substituted in the place of the other rack and keg.

In testimony whereof, I have affixed my signature in the presence of two witnesses.

HERMAN H. A. LEHMANN.
